UNITED STATES PATENT OFFICE.

JOHN W. BOWER, OF KILLBUCK, OHIO.

STRAINER.

Application filed October 1, 1924. Serial No. 741,045.

The present invention appertains to a strainer and is particularly designed for use in straining milk and similar fluid.

The prime object of the invention is to provide a support for the strainer whereby said strainer may be supported on different sized pails, buckets, or similar containers.

Another very important object of the invention is to provide a supporting structure for a strainer which will hold the latter steady over a pail, bucket, or other similar container.

A still further object of the invention is to provide a device of this nature with a very simple and efficient construction, one which will be reliable, inexpensive to manufacture, strong, durable, convenient, easy to manipulate and well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the device embodying the features of my invention,

Figure 2 is a vertical section through a portion thereof, the remaining portion being in end elevation,

Figure 3 is a top plan view of the device, and

Figure 4 is a detail perspective view showing an end of one of the adjustable rods.

Referring to the drawing in detail it will be seen that the strainer is designated generally by the letter S and in the present instance is provided with a conical shaped body 1 which is reduced intermediate its ends so as to provide a shoulder 2 both interiorly and exteriorly, the portion 3 below the shoulder forming a spout. A sheet of straining material of a foraminous nature or the like as indicated at 4 is fixed on the interior side of the shoulder 2 and spans the intermediate interior of the strainer.

The supporting device is indicated generally by the letter T and consists of a plate 5 having two of its opposite edges bent to provide sleeves 6 which in the present instance are substantially rectangular in end elevation. Channel plates 7 are disposed in these sleeves and are of a semi-cylindrical formation having their edges soldered,

welded, or otherwise fixed to the tops of the sleeves 6. Four rods 8 are associated with these sleeves 6 and channel plates 7, one being inserted in each end of each sleeve. 60 These rods are slidable in and out of the sleeves and are snugly received within the channel plates 7 so as to be frictionally engaged by the same, whereby they will retain the position to which they have been moved 65 unless otherwise interfered with. The rods 8 of the supporting structure stand outwardly in pairs, a plate 9 bridging each pair being provided with end sleeves 10 for receiving the rods. These rods are fixed to 70 the plates either by means of welding or solder or may even be frictionally engaged therewith. Each plate is provided at its ends with depending lugs 11 and the outer terminals of the rods 8 are bent downwardly 75 to form lugs 12. These lugs 11 and 12 are adapted to straddle the edge of a pail, bucket, or like container and it is evident that the rods may be slid in the sleeves 6 so that they may be adjusted properly to fit 80 different sizes in pails, buckets, or similar containers.

From the above description it will be seen that the supporting structure is readily adjustable and that it will hold the strainer proper in a steady position over a pail or the like for straining milk or the like. The device is also capable of being manipulated and possesses a very simple and inexpensive construction.

While the preferred embodiment of the invention has been described in detail, it will be understood that I do not wish to be limited to the particular construction set forth, since various changes in the form, material, proportions and arrangement of parts, and in the details of construction may be resorted to without departing from the spirit and scope of the invention as hereinafter claimed or sacrificing any of its 100 advantages.

Having thus described my invention, what I claim as new is:—

1. In a device of the class described, including a plate provided with sleeves at 105 its ends, semi-cylindrical channel plates having their edges fixed to the tops of the sleeves and disposed in the sleeves, and a plurality of rods slidable within the channel plates and frictionally engaged thereby so that they may be adjusted to different positions,

2. In a device of the class described, an elongated plate provided at its opposite ends with elongated sleeves, rods slidably disposed in the opposite ends of each sleeve and being provided with terminal depending lugs, and transverse plates connecting the rods at each side of the first named plate, said plates being provided with depending lugs spaced from the first mentioned lugs and substantially parallel therewith.

3. In a device of the class described, a plate provided at its opposite ends with elongated sleeves substantially rectangular in cross section, semi-cylindrical channel plates disposed in the sleeves, rods disposed in the opposite ends of each sleeve and frictionally engaged by the said channel plates whereby the said rods may be adjusted to different positions, said rods being provided with terminal depending lugs and transverse plates carried by and connecting the said rods at opposite sides of the first named plate, said transverse plates being formed

with depending lugs spaced from the first mentioned lugs and substantially parallel therewith.

4. In a device of the class described, the combination of a substantially rectangular plate provided at its opposite ends with elongated sleeves, semi-cylindrical channel plates disposed in said sleeves and having their edges fixed to the tops thereof, a plurality of rods slidable within said sleeves and frictionally engaged by the said channel plates so that they may be adjusted to different positions, lugs formed on the outer free ends of the rods, said rods being arranged in pairs, and substantially wide plates extending across and secured to the rods of each pair, the outer edges of said plates being formed immediately adjacent the ends thereof with depending lugs spaced from the first mentioned lugs and positioned substantially parallel thereto.

In testimony whereof I affix my signature.

JOHN W. BOWER.
